DESIGN FOR A PRESSURE REGULATOR FOR BUTANE GAS SYSTEMS

Ollie Z. Mathews, Dallas, Tex., assignor to Dallas
Engineering Company, Dallas, Tex., a partner-
ship

Application June 17, 1946, Serial No. 130,780

Term of patent 14 years

(Cl. D78—1)

To all whom it may concern:

Be it known that I, Ollie Z. Mathews, a citizen of the United States of America, residing at Dallas, in the county of Dallas and State of Texas, have invented a new, original, and ornamental Design for a Pressure Regulator for Butane Gas Systems, of which the following is a specification, reference being had to the accompanying drawing, forming a part thereof.

Fig. 1 is a side elevational view of a pressure regulator for butane gas systems, showing my new design.

Fig. 2 is a plan view,

Fig. 3 is a bottom plan view, and

Fig. 4 is an end elevation of the same.

I claim:

The ornamental design for a pressure regulator for butane gas systems, as shown.

OLLIE Z. MATHEWS.
